CLAIM

The ornamental design for a grouser cage for compacting and preparation of soil and seeding apparatus, as shown and described.

DESCRIPTION

FIG. 1 is a front-top-left view of a grouser cage for compacting and preparation of soil and seeding apparatus showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right elevational view thereof;

FIG. 7 is a left elevational view thereof;

FIG. 8 is a reduced front-top-left perspective view of the grouser cage for compacting and preparation of soil and seeding apparatus in an exploded configuration; and,

FIG. 9 is a reduced left plan view of grouser cage for compacting and preparation of soil and seeding apparatus in the exploded configuration.

The broken lines showing cleats in FIGS. 1, 2, 3, 4, 5, and 8 are included for the purpose of showing environmental structure and form no part of the claimed design.
